UNITED STATES PATENT OFFICE.

ELMER F. AFFELDT, OF RICHMOND, VIRGINIA.

TEE STAND.

Application filed May 21, 1923. Serial No. 640,499.

To all whom it may concern:

Be it known that I, ELMER F. AFFELDT, a citizen of the United States, residing at Richmond, in the county of Henrico and 5 State of Virginia, have invented new and useful Improvements in Tee Stands, of which the following is a specification.

This invention contemplates the provision of a tee stand for golf courses, wherein receptacles for sand and water, means for supporting a towel, and a brush for cleaning the golf balls when necessary are conveniently arranged in a small compact stand.

15 The nature and advantages of the invention is better understood when the following detailed description is read in connection with the accompanying drawings, the invention residing in the construction, combination and arrangement of parts as claimed. 20 In the drawings forming part of this specification, like numerals of reference indicate similar parts in the several views, wherein:

Figure 1 is a side elevation of a stand 25 constructed in accordance with the present invention,

Figure 2 is a detail view of the bucket supporting arm.

Figure 3 is an enlarged sectional view 30 taken through the sand bowl and in support.

Figure 4 is a sectional view taken on line 4—4 of Figure 1.

Figure 5 is a detail view of the direction 35 arrow.

Figure 6 is a sectional view through the base.

Referring to the drawings in detail, 10 indicates a circular base designed to make 40 good contact with the ground, especially soft uneven surface, although this base may vary in design without departing from the spirit of the invention. Rising upwardly and extending inwardly are the arms 11 forming part of the base structure, the arms 45 being secured to and supporting the collar 12 in which the tubular standard 13 is threaded, or to which the standard is otherwise suitably connected. This standard 50 supports a receptacle or sand bowl 14 which of course can be of any size or configuration. The standard 13 is internally threaded at its upper end to accommodate the plug 15 which is formed with a head 16, and the bottom of 55 the sand bowl reposes on this head as clearly shown. Arranged within the bowl and re-

posing upon the bottom of the latter is a base 17 of a coupling member utilized for a purpose to be hereinafter described, and this base 18 is secured to the head 16 by 60 means of fastening elements 20 which pass through the bottom of the sand bowl as illustrated. This construction permits the sand bowl to be conveniently removed from the standard 13 at any time it is necessary 65 or desirable to do so for any purpose whatsoever.

The coupling member just referred to is utilized to associate the supporting arm for the water bucket with the sand bowl, and as 70 clearly shown in the drawing, this supporting arm has its lower end offset as at 21 for association with the coupling member 18. The arm itself is vertically disposed as indicated at 22, and by reason of the offset portion 21, the arm is arranged to one side of the sand bowl as shown in Figure 1. The arm 22 can be of any suitable height, and is coupled as at 23 with a horizontally disposed extension 24 from which the water bucket 80 25 is suspended immediately above the sand bowl. The bucket 25 is suspended by means of clamps 26 which can be easily and conveniently removed from the extension 24 of the supporting arm when desired. These 85 clamps are preferably constructed to engage and support a direction arrow represented at 28, and disposed immediately above and in parallelism with the extension 24 of the bucket supporting arm. This arrow is 90 adapted to contain an indicia concerning the number of the green and the distance in yards, the arrow director being pointed in the direction of play.

Secured to the underside of the sand bowl 95 is a substantially L-shaped bracket 29, depending branch of which supports a brush 30 adjacent one side of the bowl, so that the golf balls can be conveniently moved across this brush when it is desired to clean the 100 balls for any purpose. Manifestly, various parts of the stand are arranged for the convenience of the user, and are also compactly disposed in the production of a cheap, yet strong and durable stand for the purpose 105 intended. Carried by the supporting arm 22 is a towel supporting hook indicated at 32, so that the towel can be conveniently arranged for the user.

While it is believed that from the foregoing description, the nature and advantages of the invention will be readily under-

stood, I desire to have it known that I do not limit myself to what is herein shown and described, and that such changes may be resorted to when desired as fall within the scope of what is claimed.

What is claimed is:—

A tee stand including a pedestal, a stand receptacle supported thereon, a horizontally arranged arm supported above the recep-

tacle, a pair of clamps detachably supported on the arm, a bucket pivotally connected with the clamp and a longitudinal element carried by the clamp and arranged above the arm and serving as a handle and also being adapted to contain indicia. 10

In testimony whereof I affix my signature. 15

ELMER F. AFFELDT.
